BREECH LOCKING MECHANISM

Clarence E. Simpson, Wilbraham, Mass., assignor
to the United States of America as represented
by the Secretary of War

Application September 22, 1949, Serial No. 117,101

8 Claims. (Cl. 89—187)

(Granted under Title 35, U. S. Code (1952),
sec. 266)

1

The invention described herein may be manufactured and used by or for the Government for governmental purposes without the payment of any royalty thereon.

This invention relates to breech locking means for firearms and particularly to an improved breech lock mechanism of the type wherein the locking members are provided with an exterior roll surface and function at right angles to the longitudinal axis of the breech member.

One example of the above type of breech locking mechanism comprises a pair of cylindrical lock members movably retained in a suitable transverse hole formed through the body portion of the bolt. When the latter member enters its closed or battery position, each of such lock members is arranged to be forced sufficiently out of the transverse hole to engage in a suitable arcuate cut provided in some fixed member of the firearm. In order to assure a positive camming action on the lock members for unlocking the bolt upon recoil, the radius of each locking cut is necessarily formed so as to be greater than the radius of the locking portion of the cylindrical lock member. In addition, sufficient clearance is maintained between the sides of the bolt and the fixed member to provide a depth of engagement between the locking members and the respective arcuate locking cuts of somewhat less than the radius of the locking members. Consequently, when the bolt recoils, sufficient angular thrust is provided between the locking and fixed members to quickly and positively initiate the camming action required to unlock the bolt.

However, the aforementioned combination of conditions introduces certain objectionable features which the present invention is designed to eliminate or overcome. One such undesirable feature in the locking means of the prior art is the difficulty of maintaining the proper clearance, commonly termed "head space," between the breech end of the barrel and the face of the bolt when the latter is in its battery position. Due to the difference in size between the radius of a locking member and that of the locking cut in which it is engaged, it can readily be seen that any change in the depth of engagement therebetween will result in a relatively greater change in the location of the point of contact between the two surfaces as measured along a line parallel to the longitudinal axis of the bolt. Variation in the location of this point of contact will, of course, permit corresponding longitudinal movement of the bolt despite the engagement of the locking members in the arcuate cuts of the fixed member.

2

It is therefore apparent that any wear induced in the locking surfaces or any accumulation of tolerances will affect the critical head space relationship of the bolt and barrel.

Accordingly, it is an object of this invention to provide in a firearm a simple, reliable, roll-type breech locking mechanism wherein ordinary wear of the moving parts or any normal accumulation of manufacturing tolerances will not seriously affect head space.

In the aforementioned prior art type of breech locking mechanism, the locking members are carried in the head of the bolt thereby requiring that a transverse hole be provided therethrough, or alternately, that a pair of axially aligned recesses be formed, one on either side of the bolt, of sufficient depth to permit full retraction of the roller members therein for unlocking of the bolt. In either event, a substantial amount of metal must be removed from the body of the bolt thereby requiring a relatively thick body portion in order to avoid the possibility of excessively weakening the structure thereof at the area of the hole or holes. Obviously, it is highly desirable that the recoiling parts of a high speed firearm be of optimum strength and yet be as light in weight as possible. Furthermore, the necessity of machining suitable arcuate locking cuts internally in the fixed member of the firearm introduces a complexity of manufacture leading to a corresponding increase in the cost of production.

It is therefore a further object of this invention to provide a breech locking mechanism wherein the locking members are carried, when in the unlocked condition, in a fixed member of the firearm thereby permitting a simple, compact and inexpensive construction.

Another detrimental feature in a breech locking mechanism having a full cylindrical locking member protruding from a transverse hole formed in the bolt is the tangential contact which exists between the surface of the locking member and the rim of the transverse hole. The strong recoil thrust of the bolt substantially increases the possibility of deformation of the cylindrical surface of the roller member at such tangential point of contact.

A particular object of this invention, therefore, is the provision of a semi-cylindrical roll-type locking member for a breech locking mechanism which will not be subject to excessive deformation during the pressure period which exists prior to the actual unlocking movement.

The specific nature of the invention as well as 55 other objects and advantages thereof will clearly

appear from a description of a preferred embodiment as shown in the accompanying drawings in which:

Fig. 1 is a top elevational view of the breech locking mechanism of this invention, drawn partly in cross-section and showing the recoiling parts in the unlocked position of the bolt.

Fig. 2 is a view similar to Fig. 1 but showing the recoiling parts in the battery position with the bolt locked.

Fig. 3 is a fragmentary cross-sectional view taken along the line 3—3 in Fig. 5 showing the manner in which the locking members engage the bolt.

Fig. 4 is a cross-sectional view taken along the line 4—4 in Fig. 5.

Fig. 5 is a side elevational view of that portion of a firearm which contains the breech locking mechanism of this invention.

Fig. 6 is an exploded view showing in isometric the novel parts of the breech locking mechanism.

Fig. 7 is a top view of the locking members showing their position relative to the barrel locking sleeve in the locked and unlocked position.

Fig. 8 is a rear end view of the breech lock actuator.

Fig. 9 is a side elevational view of the bolt assembly shown partly in cross-section.

Fig. 10 is a view similar to Fig. 4 but showing an alternate method of construction for the locking members which are here shown in the unlocked position.

Referring to the drawings, there is shown in Fig. 5 a fragmentary portion of a firearm embodying the breech locking mechanism of this invention. A hollow cylindrical bolt locking sleeve 5 is fixedly secured in any suitable manner to some immovable portion (not shown) of the firearm. A conventional barrel 7 is removably secured to sleeve 5 by a pair of oppositely disposed bayonet lugs 6 (Figs. 1-2). Barrel 7 is, of course, provided with a chamber 8 into which cartridges 9 are arranged to be fed by means of suitable mechanism (not shown). A breech lock actuator 10 is slidably mounted in the firearm and is provided with an arch-like front portion 11 arranged to fit about the top half of sleeve 5. Extending rearwardly from portion 11 is a pair of rectangular arms 12 each arranged to slidably fit in a rectangular slot 13 provided on either side of sleeve 5. An actuating slide 14 is slidably retained within the firearm and is provided with a stepped shoulder portion 15 as shown in Fig. 5 for contact with actuator 10.

The rear end portion of hollow sleeve 5 is provided with an axial rectangular opening 16. A reciprocating bolt 18 is provided with a front end portion 17, hereinafter referred to as a bolt head and such bolt head is shaped to slidably enter into opening 16 of sleeve 5. A longitudinal hole 19 extends through bolt head 17 and serves as a tunnel for a firing pin 20. Hole 19 is axially aligned with a longitudinal rectangular channel 21 arranged to slidably receive the rectangular rear end 22 of firing pin 20. The sides of channel 21 are cut away as shown at 23 in Fig. 6 to form a pair of upstanding substantially rectangular lugs 24 which are provided with an arcuate front edge 25. A pin 26 extends transversely through the rear end 22 of firing pin 20 and is arranged to protrude on either side thereof so as to engage with the arcuate front edges 25 of lugs 24.

A longitudinal rib 27 extends along either side of bolt 18 rearwardly of bolt head portion 17. Ribs 75

27 are arranged to slidably engage in a mating channel 28 formed in a bolt extension member 29. The ends of pin 26 are press-fitted or otherwise suitably fixed within the sides of bolt extension 29. As a result, the recoil movement of bolt extension 29 will be correspondingly transmitted to bolt 18 as long as pin 26 is engaged with the arcuate front edges 25 of lugs 24.

Bolt locking sleeve 5 is provided with a second rectangular opening 30 arranged to intersect slots 13 and axial opening 16 at substantially right angles thereto. A vertically disposed semi-cylindrical groove 31 is formed in either side of bolt head 17 and is arranged to align with rectangular opening 30 when bolt 18 reaches its battery position relative to barrel 7.

In order to positively lock bolt 18 to fixed sleeve 5 prior to the discharge of a cartridge in the firearm, there is provided a locking member 32 having a substantially semi-cylindrical body 33 arranged to mate snugly in the groove 31 on the right hand side of bolt head 17. The groove-engaging portion of body 33 is slabbed as best shown at 34 so that locking member 32 will disengage completely from groove 31 with a minimum amount of travel. Extending outwardly from the top of body 33 is a relatively thin rectangular arm 35 substantially half the width of body 33 itself. Since arm 35 extends across the entire top of body 33, there is thus formed a stepped portion 37 for a purpose to be explained. Substantially midway along the vertical height of body 33 and on the side from which arm 35 extends, there is formed an arcuate cam surface 42. The free end of arm 35 terminates in an angular cam surface 36.

A second locking member 45 is likewise provided to engage in the opposite groove 31, i. e., the groove formed in the left hand side of bolt 18. Locking member 45 is similar to previously described member 32 in that there is provided a body 46 having a stepped portion 47 at the top thereof, an arcuate cam surface 48 on the side, a flat slabbed surface 49 across the groove-engaging portion, and an arm 50 extending therefrom and terminating in an angular cam surface 51. However, there exists two differences between locking members 32 and 45, not in construction of their various portions but in the location thereof. While body 33 has its arcuate cam surface 42 on the side from which arm 35 extends, arcuate cam surface 48 is located on the side of body 46 which has the stepped portion 47. In addition, the angular cam surface 36 at the end of arm 35 slopes in the opposite direction from angular cam surface 51 of arm 50.

Locking members 32 and 45 are assembled into sleeve 5 from opposite sides of transverse opening 30 whereby bodies 33 and 46 are oppositely disposed with arms 35 and 50 in adjacent relationship, the free end of each arm being supported by the stepped portion of the opposite body. As a result, arcuate cam surfaces 42 and 48 are oppositely aligned and face substantially rearwardly as shown in Fig. 6. At the same time, angular cam surfaces 36 and 51 both face forwardly but due to the fact that arms 35 and 50 lie side by side, cam surface 36 is disposed behind cam surface 51 by an amount substantially equivalent to the width of arm 50.

Arch-like portion 11 of breech lock actuator 10 is provided with a pair of angular cam cuts 39 arranged to slope in a direction conversely to angular cam surfaces 36 and 51 on the ends of arms 35 and 50, respectively, and to engage the

latter surfaces simultaneously. In order to achieve such simultaneous contact with cam surfaces 36 and 51 which, as explained above, lie in staggered relationship, cam cuts 39 must be correspondingly offset in actuator 10. This is accomplished by the provision of a shelf 40 projecting rearwardly from arch-like portion 11 on the left side thereof. The left hand cam cut 39 is formed in such shelf and therefore is disposed rearwardly of the right hand cam cut by an amount sufficient to insure simultaneous engagement with cam surfaces 36 and 51. Locking member bodies 33 and 46 are also each provided with a sloping surface 38 and 44, respectively, extending downwardly from the top thereof and arranged to provide clearance for the interior curvature of arch-like portion 11. A pair of curved cam surfaces 41 is provided in the oppositely disposed portions of actuator arms 12 slightly rearwardly of the arch-like portion 11. Cam surfaces 41 are shaped to coact with arcuate cam surfaces 42 and 48 in locking member bodies 33 and 46, respectively.

As shown in Fig. 10, locking member 45 may be alternately constructed to include the second arm 50 extending from the bottom of body 46 and parallel to the upper arm so as to form a pair of identical arms 50. In such event, locking member 32 would be similarly provided with a pair of arms 35. The provision of a second arm for each locking member 32 and 45 would, of course, provide a relatively stronger construction should the single arm type of locking member prove too weak for the purpose required.

The battery position of the recoiling parts at the moment of firing is illustrated in Fig. 2. When cartridge 9 is fired, the gases evolved cause actuating slide 14 to recoil in a manner conventional to firearm art. The recoiling movement of slide 14 is in turn transmitted to actuator 10 which contacts bolt extension 29 and consequently all three parts recoil together. As actuator 10 moves rearwardly, angular cam cuts 39 simultaneously contact the conversely sloped cam surfaces 36 and 51 at the ends of locking member arms 35 and 50, respectively, and force locking bodies 33 and 46 out of the semi-cylindrical grooves 31 in bolt head 17. As soon as bolt 18 is completely unlocked and free to move rearwardly, pin 26, which heretofore has been moved along the cutaway portion 23 of bolt 18 and has withdrawn firing pin 20 to its pre-fired position, comes in contact with the arcuate front edges 25 of lugs 24. At this time, the recoiling movement of actuator 10 is stopped by contact of breech lock arch-like portion 11 with some fixed part (not shown) in the firearm. However, bolt extension 29 continues to recoil and carry with it the bolt 18 by means of pin 26 thereby effecting extraction of the fired round from barrel chamber 8. During this portion of recoil movement, suitable latch means (not shown) in extension 29 engages bolt 18 so that when the former is finally halted by a conventional buffer mechanism (also not shown), the recoil movement of bolt 18 is effectively halted as well. Counter-recoil of the moving parts of the firearm is now ready to take place.

Since bolt 18 and bolt extension 29 are latched together as mentioned above, they move forwardly simultaneously until a forwardly facing shoulder 43 at the bottom of bolt 18 contacts the front face of bolt locking sleeve 5. At this point bolt 18 and bolt extension 29 have become unlatched and furthermore bolt 18 is now fully

home with semi-cylindrical grooves 31 in alignment with locking bodies 33 and 46. Just prior to the occurrence of the unlatching action, bolt extension 29 has contacted the ends of breech lock actuator arms 12 and consequently counter-recoil movement is transmitted thereto. Thus, as bolt extension 29 and breech lock actuator 10 move forwardly, the curved cam surfaces 41 of the latter act upon the arcuate cam surfaces 42 and 48 of locking members 32 and 45 to cam locking bodies 33 and 46 into engagement with the semi-cylindrical grooves 31 on either side of bolt head 17. Bolt extension 29 and breech lock actuator 10 continue to move forwardly until the latter is stopped by contacting shoulder 45 in actuating slide 14. During this period of counter-recoil, pin 26 which is fixedly secured to bolt extension 29 moves out of engagement with lugs 24 and rides along cutaway portion 23 in bolt 18 thereby carrying firing pin 20 forwardly to fire a cartridge 9 and initiate the recoil cycle previously described.

It will be noted, as shown in Fig. 3, that the configuration of locking bodies 33 and 46 assures a full mating contact with each semi-cylindrical groove 31. This close fit will be maintained regardless of any variation in the depth of engagement between locking members 32 and 45 and bolt 18 due to a possible fluctuation in tolerances or the occurrence of wear in the locking surfaces. Thus, once bolt 18 is locked in battery position, any movement along its longitudinal axis which could affect headspace is substantially eliminated. Accordingly, it is readily apparent that the breech locking mechanism of this invention produces a locking engagement between the reciprocable bolt and a fixed member of the firearm which is far superior to the tangential point of contact existing in the prior art type of breech lock previously described.

Another advantageous feature provided by the breech lock mechanism of this invention is the simplicity of providing locking grooves in the bolt itself rather than in the fixed member of the firearm as in the prior art type of mechanism. The locking recesses need only be of sufficient depth to assure full contact with the semi-cylindrical surfaces of the locking members in contrast to the full transverse hole carried by the prior art type of bolt. Simplicity of manufacture is, of course, a vital factor in reducing the cost of production. Furthermore, since comparatively little stock is removed from the bolt in order to form grooves 31, there is here provided a comparatively stronger bolt than would be required with the prior art type of breech lock mechanism.

Referring again to Fig. 3 of the drawings, it will be noted that the sides of locking bodies 33 and 46 are arranged to fit snugly into semi-cylindrical grooves 31 in bolt head 17 as well as against the sides of sleeve 5 formed by opening 30. It can thus be readily seen that the recoil thrust of locking members 32 and 45 is distributed over a much greater area of bolt sleeve 5 than in the prior type wherein the surface of the roller member is tangent to the relatively sharp rim produced by the transverse hole in the bolt. Excessive wear and deformation of the locking members are consequently kept to a minimum by the larger area of surface contact provided when the locking members of this invention are in a bolt locking position.

I claim:

1. In a firearm having a barrel, a reciprocable

bolt, and a firing pin slidably mounted in the bolt, the combination of, a tubular member fixedly secured within the firearm and having one end arranged to slidably receive the front end of the bolt, means at the opposite end of said tubular member for detachably retaining the breech end of the barrel, a bolt extension having a channel for slidably receiving the rear end of the bolt, means for fixedly securing the firing pin to said bolt extension, an actuator member slidably engaged with the exterior of said fixed tubular member and arranged to transfer recoil movement thereof to said bolt extension, lug means on the bolt for engagement with said firing pin securing means whereby rearward movement of said bolt extension retracts the bolt and firing pin, a pair of locking members slidably retained in said tubular member and arranged for movement transverse of the longitudinal axis of the bolt, a first means in said actuating member for camming said locking members outwardly to unlock the bolt from said fixed tubular member, and a second means in said actuator member for camming said locking members inwardly to engage with and lock the bolt to said tubular member in a battery position.

2. In a firearm having a fixed barrel and a reciprocable bolt, the combination of, a tubular member fixedly secured within the firearm, means at the front end portion of said tubular member for releasably retaining the barrel thereto, the rear end portion of said tubular member arranged to receive the front end portion of the bolt, a reciprocating actuator member slidably engaged with the exterior of said tubular member, said tubular member having an opening therethrough disposed at right angles to the longitudinal axis thereof, a pair of locking members slidably retained in said rectangular opening and arranged to engage with the bolt, each of said locking members having a body portion and an arm extending therefrom, each of said body portions having an arcuate surface thereon, said arms having an angular cut at the free end thereof, first cam means in said actuator member arranged to contact said angular cuts at the free end of said arms of said locking members whereby recoil movement of said actuator member actuates said locking members outwardly to disengage from the bolt, and second cam means in said actuator member arranged to contact said arcuate surfaces on said body portions whereby counter-recoil movement of said actuator member returns said locking members into locking engagement with the bolt.

3. Means for locking and unlocking a longitudinally reciprocating bolt in a firearm comprising, a tubular member fixedly secured in the firearm, said tubular member having a substantially rectangular opening therethrough disposed transversely of the longitudinal axis thereof, the bolt having a semi-cylindrical vertical recess on either side thereof arranged to be aligned with said rectangular opening in said tubular member when the bolt reaches battery position, a pair of locking members each having a substantially semi-cylindrical body arranged to fit snugly within said recesses in the bolt, a relatively narrow arm portion extending outwardly from the top of each of said bodies, a downwardly stepped portion on the top of each of said bodies adjacent said arm portions, said locking members arranged to be inserted into opposite ends of said rectangular opening in said tubular member with the arm

of one member slidably supported on the stepped portion of the other member whereby said bodies are oppositely disposed and aligned with said recesses in the bolt when the latter is in battery position, first cam means for simultaneously actuating said locking members transversely of the longitudinal axis of the bolt into locking engagement with said recesses in the bolt, and second cam means for simultaneously actuating said locking members out of engagement with the bolt.

4. The construction of claim 3 wherein said locking members are each provided with a pair of parallel arms disposed at the top and bottom of said bodies and extending outwardly in the same direction, and said bodies are each provided with a stepped portion on the top and bottom thereof for slidably supporting the free ends of said arms.

5. In a firearm having a barrel, the combination of, a tubular member fixedly mounted in the firearm, means in said fixed tubular member for releasably securing therein the breech end of the barrel, a longitudinally reciprocable bolt having a substantially rectangular bolt head, said bolt head having a semi-cylindrical groove on either side thereof, said fixed tubular member having a rear end portion arranged to slidably receive said bolt head into battery relationship with the barrel, said tubular member having a pair of oppositely disposed longitudinal slots extending forwardly from the rear end thereof, said tubular member also having a substantially rectangular opening arranged to extend transversely therethrough and intersect said slots, a pair of locking members having a body portion and an arm extending outwardly from the top thereof, said body portion arranged to slidably fit into said transverse opening and engage into said grooves in said bolt head, said arm of one locking member extending toward said body portion of the other locking member and lying in adjacent relationship, a reciprocable actuator having an arch-like body portion and a pair of legs extending rearwardly therefrom, said arch-like portion arranged to fit about the top half of said tubular member with said legs slidably engaged in said slots thereof, first cam means in said actuator for camming said locking members outwardly to disengage from said bolt head upon the recoil stroke of said actuator, and second cam means in said actuator for camming said locking members inwardly to reengage with said grooves in said bolt head upon the counter-recoil stroke of said actuator.

6. In a firearm, a breech locking mechanism comprising, a tubular member fixedly secured in the firearm, a longitudinally reciprocating bolt having an integral head portion arranged to extend into said fixed tubular member when in a battery position, said bolt head portion having a semi-cylindrical vertically disposed groove on either side thereof, said tubular member having a transverse opening therethrough arranged to align with said grooves when said bolt is in its battery position, a pair of locking members each arranged to slidably fit into one end of said transverse opening in said tubular member, said locking members having a body and an arm extending outwardly from the top thereof, said bodies having a stepped portion on the top thereof, located so as to support the end of said arm of the opposite one of said locking members, said bodies having a substantially arcuate portion arranged to engage snugly into

said grooves of said bolt and having flat portions on either side thereof rearwardly of said arcuate portions for slidable engagement with the walls of said transverse opening in said tubular member, an arcuate cam surface on each of said bodies located substantially midway along the vertical axis thereof and arranged to face rearwardly when said locking members are assembled, an angular cam surface at the free end of each of said arms arranged to face forwardly when said locking members are assembled, and reciprocable means for engaging said angular cam surfaces on said arms to cam said locking members out of engagement with said bolt during recoil and for engaging said arcuate cam surfaces on said locking bodies to cam said locking members into engagement with said bolt during counter-recoil.

7. In a firearm, a breech locking mechanism comprising, a tubular member fixedly secured in the firearm, a longitudinally reciprocating bolt, an integral head portion arranged to extend into said fixed tubular member when in a battery position, said tubular member having a transverse opening therethrough, a pair of locking members arranged to slidably fit into one end of said transverse opening, said locking members having a body and an arm extending outwardly from the top thereof, an angular cam surface at the free end of each of said arms, said arms arranged to lie side by side in said tubular member whereby said angular cam surface on one of said arms is disposed forwardly of the other, a reciprocable actuator member having an arch-like portion, a pair of angular cam cuts in said arch-like portion, and a rearwardly extending shelf disposed on one side of said arch-like portion and arranged to contain the angular cam cut in such side whereby one of said cam cuts is located rearwardly of the other, all arranged

and adapted whereby said angular cam cuts in said actuator member simultaneously contact said angular cam surfaces at the free ends of said arms to cam said locking members out of engagement with said bolt during recoil.

8. In a firearm, a breech locking mechanism comprising, a tubular member fixedly secured in the firearm, a longitudinally reciprocating bolt arranged to extend into said fixed tubular member when in a battery position, a pair of oppositely disposed locking members slidably retained in said fixed tubular member for movement in a direction transverse of the longitudinal axis of the bolt, said tubular member having a slot on either side extending forwardly from the rear face thereof, a reciprocable actuator having an arch-like body portion and a pair of legs extending rearwardly therefrom, said actuator arranged to slidably engage said tubular member with said arch-like portion surrounding the outer periphery of the former and with the inner sides of said legs in said slots, said arch-like portion having a pair of angular cam cuts therein for camming said locking members out of engagement with said bolt whereby the latter is free to recoil, and each of said legs having an arcuate cam surface in opposed relationship for camming said locking members into engagement with said bolt whereby the latter is locked to said tubular member.

CLARENCE E. SIMPSON.
